(57) **ABSTRACT**

A new and distinct variety of carnation plant characterized
by large, full-size spray type flowers, which open fully
without bursting the calyx and causing splits.

1 Drawing Sheet

1

Botanical classification: The present invention relates to a
new and distinct variety of hybrid *Dianthus caryophyllus*.
The varietal denominator of the new variety is 'CFPC Tess'.

BACKGROUND OF THE INVENTION

The present invention relates to a new and distinct variety
of carnation plant, named 'CFPC Tess', which was originated
by me from a cross made in a controlled breeding
program. The female, or seed, parent is unpatented and
identified as 990366; the male, or pollen, parent is an
unknown seedling. The primary objective of the controlled
breeding program was to produce a new purple-flowered
cultivar for the 'Adorable' series of pot carnations. The
closest commercial cultivar in color to the new cultivar of
which I am aware is the carnation 'CFPC Passion' (U.S.
Plant Pat. No. 10,416).

'CFPC Tess' differs from its female parent 990366, in
having a purple flower color, while 990366 has a white
flower color with markings. No comparison with male
parent is possible, as the male parent is unknown. 'CFPC
Tess' differs from its closest known commercial cultivar,
'CFPC Passion', in that 'CFPC Tess' is an 'Adorable' type
carnation having a shorter stature, as well as a larger, fuller,
more double flower.

SUMMARY OF THE INVENTION

Among the novel characteristics possessed by the new
variety which distinguishes it is a large, full-spray type
flower, which opens fully without bursting the calyx and
causing splits. When grown in 4½ plastic pots in Salinas,
Calif., plant diameter averages about 7 inches. Pinched
plants are about 6½ inches tall and flowers are about 2 inches
average diameter with a crown higher than about ¾ inches.
Foliation is about 3¼ inches long and about ½ inches wide.

Asexual reproduction and flowering of this new cultivar
by side shoot cuttings as performed in Salinas, Calif., shows
that the foregoing and other distinguishing characteristics

2

come true to form and are established and transmitted
through succeeding propagations.

BRIEF DESCRIPTION OF ILLUSTRATIONS

The accompanying photographic illustration shows a
typical specimen of the new variety in color as nearly true
as it is reasonably possible to make in a color illustration of
this character.

DESCRIPTION OF THE NEW VARIETY

Referring now specifically to the new and distinct variety
of carnation plant the following is a detailed description of
'CFPC Tess' with color description where indicated by
reference to The Royal Horticultural Society Colour Chart,
except where common terms of color definition are
employed.

The new variety of carnation plant as herein described
may vary in slight detail due to climatic, soil and cultural
conditions under which the variety may be grown, the
present description being of the variety as grown at Salinas,
Calif.

25 **Plant:**

Height.—About 6½ inches tall.

Form.—Herbaceous.

Growing habit.—Semi-upright.

Blooming habit.—As a spray, pot variety.

Blooming season.—Year round.

Rooting time.—About 18 days.

Number of new flower-bearing shoots per cutting.—
About 4 to 6 shoots per cutting.

Mutation prone.—No.

Disease resistance.—Superior to *Fusarium oxysporum*,
F. graminearum and root-rots such as damping off,
water molds and the like.

Temperature tolerance.—At least 60° F. to 90° F.

Foliation:

Color.—Upper side: near 136A; lower side: near 137B.
Size.—Length: about $3\frac{1}{4}$ inches; width: about $5\frac{1}{16}$ inches.
Quantity.—Numerous.
Shape.—Lanceolate.
Texture.—Smooth.
Ribs.—Central keel.
Stem color.—Near 138C.

Bud:

Shape.—Ovoid.
Color.—Near 138B.
Size.—Length: about $1\frac{5}{16}$ inches; diameter: about $7\frac{1}{16}$ inches.

Calyx:

No. of lobes (sepals).—Five.
Size.—Length: about $\frac{5}{16}$ inches; width: about $\frac{1}{4}$ inches.
Color.—Outside: near 138B; inside: near 138C.

Bloom:

Shape.—Rounded.
Size.—Diameter (average): about 2 inches; depth (average): about $\frac{7}{8}$ inches.
Borne.—As a spray.
Color.—General tonality: purple; Upper side: near 74A; Lower side: near 74B; Center: near 74A; Outer petals: near 74A.
Permanence.—Dry up on receptacle.

Keeping quality.—Very good, over three weeks.

Fragrance.—Slight.

Petalage:

Number.—Approximately Forty two.
Outer petals.—Length: about $1\frac{3}{4}$ inches; Width: about $1\frac{3}{8}$ inches.
Central petals.—Length: about $1\frac{1}{2}$ inches; Width: about $\frac{3}{4}$ inches.
Texture.—Smooth.
Appearance.—Shiny.
Form.—Fan-shaped.

Reproductive organs:

Stamen.—None (male sterile).
Anthers.—None.
Filaments.—None.
Pistil.—Number: one. Color: White (whiter than 155D).
Stigma.—Number: 3 (trilobed); Color: White (whiter than 155D) with tips of near 74B.
Fertility.—Male: sterile; Female: Not observed.
Ovary.—Shape: conical; Color: base near 138D, body near 138A, apex near 138A.

I claim:

1. A new and distinct variety of carnation plant identified as 'CFPC Tess', substantially as shown and described.
